EXERCISING APPARATUS

Paul A. Bailleaux, Glendale, Calif.

Application October 2, 1944, Serial No. 556,772

4 Claims. (Cl. 272—81)

1

This invention relates to portable exercising apparatus.

It is an object of this invention to provide such apparatus which may be readily set up for use or folded into a compact form to occupy reduced space and to be readily portable.

It is another object of this invention to provide such apparatus which is entirely self supporting when in use, and which is adapted to fold into a base member when not in use.

It is another object of this invention to provide such apparatus adapted for use in connection with a variety of body development exercises.

It is another object of this invention to provide such apparatus which may be readily adjusted to support the body in a reclining position and at a desired inclination.

It is another object of this invention to provide such apparatus embodying a novel form of chest weight mechanism.

Chest weight mechanisms usually require a support capable of resisting a substantial force acting in a generally horizontal direction. In exercisers embodying such apparatus, and intended for home use or to be portable, it is difficult to provide an adequate support for this purpose. It is thus another object of this invention to provide improved support means for such mechanism.

It is another object of this invention to provide such apparatus which may be readily set up for use or folded into a compact form to occupy reduced space and to be readily portable and incorporating chest weight mechanism, wherein the means which serves to maintain such mechanism in position for use, serves additionally to provide a table for supporting the body in a reclining position.

This invention possesses many other advantages and has other objects which may be made more easily apparent from a consideration of one embodiment of the invention. For this purpose there is shown a form in the drawing accompanying and forming part of the present specification. This form will now be described in detail, illustrating the general principles of the invention; but it is to be understood that this detailed description is not to be taken in a limiting sense, since the scope of the invention is best defined by the appended claims.

Referring to the drawings:

Figure 1 is a longitudinal sectional view of apparatus embodying the invention;

Figure 2 is an end elevation, partly in section,

on an enlarged scale, taken on line 2—2 of Figure 1;

Figure 3 is a detail section taken on line 3—3 of Figure 1, certain parts being omitted for clarity; and

Figure 4 is a detail section taken on line 4—4 of Figure 2.

Referring to Figure 1 of the drawings, apparatus incorporating the invention, as set up and arranged for one type of exercise, is shown in full lines, the apparatus arranged for a different type of exercise being shown by broken lines. The chest weight mechanism is indicated generally by the numeral 1 and is mounted in a rectangular box-like base member or cabinet 2, the lid 3 of the box serving, when desired, to maintain such mechanism in position for use. When not in use, the chest weight mechanism 1 may be lowered so as to be enclosed within the base 2, as indicated by 1—a in Figure 1, the lid 3 serving to close the top of the base. In addition to exercises involving the use of chest weights, it is intended that the apparatus be used in connection with various bodily development and posture exercises requiring the body to be supported in a reclining position, and for this purpose a body supporting member or table which may be inclined at any one of several angles is provided. Thus, by supporting the mechanism 1 at different positions on the base 2, for example as indicated by 1—b, the lid 3 may form such a table supported at an inclination shown at 3—b. Other adjusted positions of the table are indicated at 3—c and 3—d.

The chest weight mechanism 1 is mounted on a tubular rectangular frame 10 having oppositely extending pintles 11, 12 at its lower end by which the frame is supported on bars 13 and 14, which may conveniently be angle irons secured to the opposite side members 15 and 16 of the base 2. The upper member 17 of the frame 10 is pivotally attached to the lid 3 near one end thereof by brackets 19 and 20 secured to the lid. The other end of the lid 3 is hingedly secured to the base 2 by conventional hinges 21.

The frame 10 and lid 3 cooperate to support each other with their connected ends above the base 2. When the frame 10 and the lid 3 are so positioned that the frame 10 is substantially vertical, the friction of the pintles 11 and 12 on the bars 13 and 14, due to the weight of the lid and the frame, is relied on to prevent movement of the pintles along these bars. The full lines of Figure 1 indicate the frame 10 in this position, wherein it forms a strut for supporting the lid 3

on the base 2. However, for inclined positions of the frame 10 corresponding to lesser inclinations of the lid 3 or the table 3, under which conditions the weight of these parts would urge the pintles 11 and 12 to move along the bars 13 and 14, pairs of spaced stop means 22 are provided on the bars for engaging the pintles 11 and 12 and preventing such movement. Since with the frame 10 inclined, the weight of the lid 3 and the frame always urges the pintles 11 and 12 to move in one direction, these stops 22 may comprise means forming notches 25 which open on one side and oppositely to said direction of movement of the frame 10.

When it is desired to lower the lid 3, it is first raised sufficiently to lift the frame 10 to free the pintles 11 and 12 from the surface of the bars 13 and 14 or from whichever pair of notches 22 they happen to be engaging, and the lower end of the frame 10 is swung to the right to cause the pintles 11 and 12 to engage the desired pair of notches 22. Or if it is desired to fold the frame 10 within the base 2, the pintles are maintained out of engagement with the angles 13 and 14 as the lid 3 and the frame 10 are lowered, until the pintles rest on the bars 13 and 14 adjacent the right hand end thereof (position 1—a of Figure 1) and the lid 3 rests on top of the base 2.

To facilitate lowering the frame 1 from the vertical position shown in Figure 1 to its folded position within the base 2, a pair of sloping bars 27 and 28 are provided on the side members 15 and 16 and above the support bars 13 and 14. Then, if the lid 3 is raised sufficiently, the frame 10 may be swung to cause the pintles 11 and 12 to rest on these bars, which will support the pintles free of the stops 22 as the frame 10 is swung to the right.

The chest weight mechanism comprises an upwardly directed guide made up of a pair of parallel rods or bars 30 which extend between the upper cross member 17 and a similar lower cross member 18 of the frame 10, and have a weight carrying member 31 freely slidable thereon. The spaced ends 32 and 33 of the member 31 are each provided with a pair of hook portions 33—a forming seats for supporting the weights 34 and 35, which may conveniently be in the form of dumb bells. A pair of spaced coaxial pulleys 36 and 37 are rotatably carried by the member 31.

A stationary member 38 is mounted on the upper cross member 17 of the frame 1 and pivotally supports a pair of pulley supports 39 and 40 for swinging movement about axes generally parallel to the rods 30. As best shown in Figures 3 and 4, the member 38 is secured to the cross member 17 by the rods 30, which pass through the cross member and a U-shaped portion 38—a of the member 38 which straddles the member 17. Pulley supports 39 and 40 respectively carry pulleys 41 and 42. An equalizing pulley 43 is rotatably mounted on the back of the member 38. As is common practice in such mechanism, the axes about which the pulley supports 39 and 40 pivot, coincide substantially with the axes of cables joining the pulleys 36 and 41, and pulleys 37 and 42, the lower pintle of the supports being hollow to accommodate such cable.

In the present instance a single cable 44 is provided, having hand grips 45 and 46 at its opposite ends. The cable 44 extends from the handgrip 45 over the pulley 41, thence down to the pulley 36, about the pulley 36 and upwardly to the equalizing pulley 43, over the pulley 43 and downwardly to the pulley 37, about the pulley 37

upwardly to the pulley 42, and over the pulley 42 to the hand grip 46. With such a cable and pulley arrangement, the load on the hand grips 45 and 46 caused by the weighted element 31 is always equalized. Further, with such an arrangement, equal and opposite movements of the hand grips cause the weighted element 31 to float or be supported by the cable without appreciable movement. Thus, exercises involving such movements may be taken against a constant resistance. When the weighted element 31 is not supported by the cable 44, it rests on the lower frame member 18, cushion means in the form of washers 49 being provided on the bars 30 between the element 31 and the member 18.

By utilizing detachable dumbbells 34 and 35 for weights in the mechanism 1, exercises involving the use of dumbbells may be taken without the need of additional equipment. To permit utilization of the apparatus for exercises requiring a reclining posture, a strap 50 is provided at the free end of the lid 3 for engaging the feet of the user. This strap 50 has a snap hook 51 at each end for detachably securing the strap to eyes 52 and 53 formed on the brackets 19 and 20.

The use of chest weight mechanism is well known and will not be described. In using this part of the apparatus, the frame 10 is positioned vertically. In using the lid 3 as an exercise table, it is positioned at a desired inclination, by engaging the pintles 11 and 12 with the appropriate stops 22. The user then takes his position on the table passing his feet beneath the strap 50. Exercises taken in an inclined position with the head down have certain known advantages. By making the table adjustable, the inclination can be accommodated to the strength of the user.

When it is desired to fold or close the apparatus, the dumbbells 34 and 35 are removed from the carrier 31, and placed on a shelf 54 provided at one end of the base 2. This shelf will also accommodate conveniently various accessories which may be used with the apparatus.

I claim:

1. In exercise apparatus, means forming a base, a chest weight mechanism including a frame supported on the base, and a member pivotally secured to the base and adapted to engage the upper end of said frame, said member and said frame cooperating to support each other with their engaged ends spaced above the base, whereby said member is inclined upwardly from its pivoted end, providing an exercise table.
2. In exercise apparatus, means forming a base, chest weight mechanism including a frame, means adjustably mounting the lower end of said frame on the base, and an inclined member hinged to the base and extending upwardly therefrom to a pivoted connection with said frame at its upper end, said member and said frame cooperating to support each other, said mounting means permitting adjustment of the lower end of said frame toward and away from the hinged connection whereby the inclination of said member may be altered.
3. In exercise apparatus, weight mechanism having a frame, a box like base structure, a member hinged to said base structure and adapted to form a lid therefor, means for supporting the lower end of said frame within said structure at spaced points along the structure, means movably connecting the upper end of said frame and the free end of the hinged member, said frame and said hinged member being adapted

to fold with respect to each other and to said structure, whereby said frame is supported within the base by said member and said support means, said member forming a closure for the base.

4. In exercising apparatus, a box-like base structure having an open top, a closure member hingedly connected at one end to said base, a weight lifting mechanism including a frame pivotally connected at one end to the free end of said closure member and having its other end extending into said box, and means within the box supporting the last named end of said frame for adjustment with respect to said hinged connection, whereby to optionally support the weight lifting frame in a substantially vertical position or in a position to alter the inclination of the closure member.
